GEORGE W. HEATH AND ALFRED C. HEATH, OF NEWARK, NEW JERSEY.

SAFETY-CLIP FOR PENS AND PENCILS.

1,145,583.

Specification of Letters Patent. Patented July 6, 1915.

Application filed June 12, 1912. Serial No. 703,232.

To all whom it may concern:

Be it known that we, GEORGE W. HEATH and ALFRED C. HEATH, citizens of the United States, residing in the city of Newark, county of Essex, and State of New Jersey, have invented certain new and useful Improvements in Safety-Clips for Pens and Pencils, of which the following is a full, clear, and exact description, such as will 10 enable others skilled in the art to which it pertains to make and use the same, reference being had to the accompanying drawings, and to letters of reference marked thereon, forming a part of this specification.

15 Our invention relates to improvements in devices for holding pens and pencils in the pocket, when the same are not in use, and has for its object, to provide an inexpensive and efficient clip provided with integral securing elements adapted to engage with apertures formed in the cap of the pen or the barrel of the pencil holder, whereby said clip is secured thereto in a positive manner, thereby eliminating all possibility of its becoming loose or accidentally disengaged from the device to which it is secured.

20 A further object of our invention is to provide a clip of the character described, which when secured to the cap of a fountain pen or barrel of a pencil holder, will have locking engagement therewith and will not have the securing means thereof project into the barrel or cap of the device, but will lie flush therewith in order to present a smooth 25 interior of the barrel.

25 In describing our invention, reference is had to the accompanying drawings, in which a preferred and a modified construction of a safety clip embodying our invention is 30 shown, and in which like letters of reference indicate corresponding parts in all of the views.

Figure 1 represents a front elevation of our device secured to the pen protecting cap. 35 Fig. 2 represents a side elevation of the same. Fig. 3 represents a cross-section of the pen protecting cap with the clip secured thereto. Fig. 4 represents a transverse section taken on lines $\alpha-\alpha$ of Fig. 3, and 40 looking in the direction indicated by the arrow. Fig. 5 represents an enlarged plan view of a modified form of safety clip. Fig. 45 5 represents a side elevation of the same; Fig. 7 represents a cross-section of the pen.

protecting cap illustrating the manner in 55 which the clip is secured to the cap.

In the drawings, *a* represents a fountain pen and *b* the protecting cap to which is permanently secured the safety clip *c* as illustrated in the drawings. The safety clip *c* 60 consists of a spring, the lower end of which is turned up at *d*, and forms one jaw of a clamp, of which the pen or pencil holder forms the other jaw, and this clamp by the action of the spring engages the pocket and 65 holds the pen or pencil securely therein. The upper end of the clip *c* is provided with two downwardly extending integral nibs *e* and *f* bent from the general plane thereof, (see Figs. 3 and 6 of the drawings), the nib 70 *f* being pierced from the body of the clip and bent at right-angles thereto as clearly indicated. These integral nibs *e* and *f* are designed to pass through suitable apertures in the pen protecting cap, or pencil holder 75 barrel, and turned over against the inside thereof in the manner shown.

In Figs. 5 and 6 of the drawings, we have shown the clip at that point where it is designed to be secured to the pen protecting 80 cap or pencil barrel with a raised or convex portion *g* so formed that when the clip is secured to the pen protecting cap of a fountain pen, or the barrel of a pencil holder, the nibs *e* and *f* will have locking engagement therewith and instead of projecting into the cap or barrel will by the action of suitable punches and dies, be turned over 85 against and force the metal of the barrel into the convex portion *g*, thereby producing a flush interior surface in the barrel, as indicated in Fig. 7 of the drawings.

The invention is not limited to the exact embodiment shown, but may be modified in various ways in the scope of the following 95 claims.

We claim:

1. A clip comprising a clamping member, a base portion integrally attached thereto, said base portion having a concaved attaching face, a lug cut from said base and bent at an angle thereto, and adapted to project into a pen barrel, and a second lug extending from the end of the base portion and at an angle thereto. 100

2. A pen clip forming an article of manufacture adapted to be fastened to a fountain pen barrel, said clip comprising a one-piece 105

sheet of spring metal relatively thin compared with its other dimensions having a base adapted to conform to the configuration of the outer surface of the barrel and having a pocket engaging member integral therewith, said base portion having a plurality of prongs integral therewith and one of said prongs adapted to be bent from the general plane of the base to fasten the clip 10 to the pen barrel, one of said prongs being an extension from an outer edge of said base.

3. A clip comprising a clamping member, a base portion integrally attached thereto, 15 said base portion having a concaved attaching face, a lug cut from said base and bent at an angle thereto and adapted to project into a pen barrel, and a second lug extending from the end of the base portion and 20 adapted to project into a pen barrel.

4. A pen clip forming an article of manufacture adapted to be fastened to a fountain pen barrel, said clip comprising a one-piece sheet of spring metal having a base adapted 25 to conform substantially to the configuration of the outer surface of the barrel and having a pocket-engaging member integral therewith, said base portion having a plurality of prongs integral therewith and

adapted to fasten the clip to the pen barrel, 30 one of said prongs being positioned at an outer edge of said base.

5. A clip comprising a clamping member, a base portion integrally attached thereto, a lug cut from said base and bent at an angle 35 thereto and adapted to project into a pen barrel, and a second lug extending from an edge of the base portion and adapted to project into a pen barrel.

6. A pen clip forming an article of manufacture adapted to be fastened to a fountain pen barrel, said clip comprising a one-piece strip of spring metal, having a relatively broad base adapted to conform to the curvature of the barrel, a prong cut from said base 45 and bent from the plane thereof, a second prong extending from one edge of said base and a relatively long pocket engaging member extending from the edge of said base 50 opposite said second prong.

This specification signed and witnessed
this 10th day of June, 1912.
